HYDRAULIC SYSTEM

Harvey W. Rockwell, Cedar Rapids, Iowa, assignor to La Plant-Cheate Mfg. Co., Inc., Cedar Rapids, Iowa, a corporation of Delaware

Application April 17, 1946, Serial No. 662,787

7 Claims. (Cl. 103—42)

1

My invention relates to means for supplying hydraulic fluid, such as a liquid or oil, under pressure and under the control of an operator for the purpose of actuating various instrumentalities. The invention is particularly concerned with the system as a whole, and more especially with an element or unit thereof for accumulating a supply of pressure fluid.

In the operation of hydraulic systems of the type mentioned, there is often an intermittent requirement for hydraulic actuation of sundry instrumentalities, for example, clutches or brakes; yet the pressure-supplying mechanism, such as a pump, is customarily attached to a motor or engine which may run continuously, or may run at varying speeds, or may cease operation from time to time. The result is that the requirement for hydraulic actuation does not necessarily coincide in point of time with the availability of hydraulic energy.

Various attempts have been made to provide some mechanism for reconciling these disparate circumstances, and in certain instances, have taken the form of pressure accumulators, which store a supply of pressure fluid for subsequent use. The fluid utilized has some bearing on the type of mechanism employed, but the problem is accentuated in the case of fluids such as liquids that are normally incompressible.

It is therefore an object of my invention to provide a hydraulic system in which there is a way of accommodating, within the limits of the structure, a widely varying demand for and a widely varying supply of pressure fluid.

Another object of the invention is to provide a way of storing a hydraulic fluid under pressure in satisfactory quantities.

An additional object of the invention is to provide a hydraulic system in which the moving parts operate relatively infrequently to reduce wear and possible service difficulties.

An additional object of the invention is to provide a hydraulic system in which the regulating mechanism is compactly arranged and assembled and is largely protected from the adverse influence of the elements or operating environment of the system.

A further object of the invention is to provide a generally improved hydraulic system.

Other objects, together with the foregoing, are attained by the preferred form of the hydraulic system of my invention, as illustrated in the accompanying drawings, in which

Fig. 1 is a schematic diagram showing the hydraulic system of my invention in one embodiment.

ment, portions of the structure being in cross section on central, longitudinal planes and other portions being illustrated diagrammatically.

Figs. 2, 3, 4 and 5, inclusive, are diagrammatic disclosures of the structure shown in Fig. 1 in various stages of the operating cycle.

While the invention can be embodied in a number of variant forms, it has successfully been incorporated in the form especially disclosed 10 herein, designed to operate the clutch and brake of a winch or windlass mechanism mounted on and propelled by a tractor and designed to derive energy for driving the hydraulic pump from the tractor engine. The winch or windlass is 15 intermittently operated, and the tractor engine operates at various times and at various speeds so that the pump is variably operated.

The windlass or winch is not shown as it is a standard device. It incorporates a standard 20 clutch mechanism 6, normally disengaged so that it does not transmit power by the action of a heavy spring. The force of the spring is indicated by an arrow 7 and is overcome by a piston 8, hydraulically actuated when the clutch is 25 to be engaged.

Somewhat similarly, the winch or windlass is also provided with a standard brake incorporating an actuating arm 9 connected by a pin 11 to a plunger 12, operating within an enclosing 30 casing 13. The brake is normally held engaged by spring force indicated by an arrow 14. The brake is released under the influence of a hydraulic mechanism 16 of standard construction.

The same engine that drives the clutch mechanism 6 is also effective to rotate a hydraulic 35 pump 21 of any suitable type capable of imparting pressure to an operating medium such as oil or other hydraulic fluid. The pump 21 is provided with an intake duct 22 leading from a reservoir 23 suitably mounted in any convenient location on the tractor. For convenience in manufacture, the reservoir 23 is preferably in the form of an elongated metal cylinder and is, at its uppermost point, provided with a filler neck 24 40 closed by a cap 26 normally effective to afford some ventilation of the interior of the reservoir 23, so that the pressure existing therein is never far from atmospheric.

During the operation of the engine and only 45 when the engine is operating, the pump 21 is effective to withdraw fluid through the duct 22 from the reservoir 23 and to discharge the oil under pressure through a conduit 27.

This conduit 27 leads to a cap 28 secured to 50 one end of the reservoir 23 but not immediately

abutting the reservoir cylinder for the reason that this otherwise open end of the reservoir is primarily closed by an intermediate head 29. The fastening devices (not shown) that hold the cap 28 to the reservoir 23 also preferably hold the interposed head 29 in position. Oil discharging from the conduit 27 flows into a hollow interior chamber 31 in the cap, and therein passes through a suitable filter or screen 33, held in position by a flange 34 pinched between an adjacent face of the head 29 and a similar face on the cap 28.

The construction and arrangement are such that all of the oil which issues from the conduit 27 must pass through the filter 33 into the interior 36 thereof. Communicating with the filter interior 36 by a short passageway 37 is a conduit 38 constituting an extension of the conduit 27 and leading from a bored passage 39 in the head 29 to a location at the other end of the reservoir 23.

This end of the reservoir is open except for the closure thereof by an intermediate head 41 and a closure cap 42, the assembly being similar to that at the initial end of the reservoir. The conduit 38 extends into a fitting 43 threaded into the cap 42 and constituting a seat 44 for a ball check valve 46. The valve is held on its seat normally by a coil spring 47 abutting the ball 46 and likewise abutting the end of a passageway 48 formed within the cap 42. Pressure fluid from the pump flows through the filter and through the conduit 38, and past the check valve 46 into the passage 48. Joining this passage is a fluid conductor 49 leading from the cap 42 to a suitable location whereat is installed a control valve 51.

The control valve can be of any suitable sort and, for example, there is illustrated a valve fabricated of a main valve body 52 having a major transverse bore 53 therethrough. In the bore is disposed a valve bobbin 54 having a suitable fit for reasonable oil tightness yet free enough for axial translation within the bore to occupy any one of several selected valving positions. Leakage along the surface of the bobbin is precluded adjacent the margins of the body 52 by suitable ring packings 55. The bobbin 54 at its upper end is reduced and is pierced to receive a fastening pin 56 for securing the bobbin to an operating lever 57. This lever is provided with an actuating handle 58 and is connected by an interposed link 59 and pivot pins 61 and 62 to the body 52. In addition, the lever 57 carries a detent roller 63 adapted in one position of the lever and bobbin to ride over a detent pin 64 movably mounted in the valve body 52 and restrained by a leaf-spring 66, held on the valve body by fastenings 67.

In addition to the detent roller 63 and cooperating structure, the valve bobbin 54 is also resiliently located by a coil spring 68 nested in a cap 69 secured to the lower portion of the valve body and abutting a flanged washer 71 encompassing a reduced portion 72 of the valve bobbin. Thus, when the valve bobbin is translated, the spring is compressed or when the bobbin and its lever are free, the spring tends to restore the bobbin to a central position as shown in Fig. 1. The fluid conductor 49 joined to the valve body 52 leads into a central ring-like or annular passage 81, which can be connected by translation of the bobbin and utilization of reduced portions 82 and 83 thereof, either to a duct 84 leading to the brake actuator 16 or to a duct 86

leading to a clutch actuator 87 including the piston 8.

When pressure fluid from the line 49 passes through the valve and through the duct 84 to the actuator 16, it is effective to overcome the urgency of the spring 14 and to release the normally applied brake by operation of the linkage 9. When pressure fluid from the duct 49 is led through the conduit 86, it enters the clutch actuator 87 and is effective therein to translate the piston 8, with the assistance of a light spring 88, to overcome the urgency of the clutch spring and to engage the normally disengaged clutch.

When the lever 58 is otherwise manipulated, 15 the ducts 84 and 86, or either of them, are cut off from communication with the pressure duct 49 and rather are placed in communication with either one of a pair of drain ducts 91 and 92, merging into a drain conduit 93 extending to 20 the head 29 and communicating by means of a passage 94 therein with the interior of the reservoir 23. In this valve position, fluid which has left the reservoir has been advanced by the pump 21, has passed through the conduit 27, 25 the filter 33, the conduit 38, the check valve 46, and the conduit 49, and has passed through the valve 51 and into either of the actuators 16 or 87, or both of them, is finally restored through the valve 51 and the return conduit 93 to the 30 reservoir 23.

Under some circumstances, the hydraulic circuit as so far described might alone almost be sufficient to produce reasonable results, but because of the disparity between the operating characteristics and times of the pump 21, and of the clutch 6 and of the brake 9, I provide in accordance with the invention, special mechanism for improving the operation. This special mechanism is preferably incorporated with the reservoir structure for ease in servicing, for protection from the elements, and for providing certain other advantages.

Consequently, the head 41 is preferably formed with a circular, cylindrical extension 96 in order 45 to define an accumulator chamber 97 substantially co-axial with and located within the reservoir 23. Operating within the cylinder 96 is a piston 98 having a close running fit with the cylinder and sealed against major leakage by a ring packing 99. With this arrangement, the piston 98 is reciprocable within the cylinder and with the cylinder defines a variable, enclosed volume forming an accumulator chamber in communication through the passageway 48 with the pressure conduit 38.

The piston is connected to a follower cup 101 by an interposed aligning pin 102, for the purpose of taking care of any minor misalignment 60 between the piston and the cup 101. This cup has an elongated skirt carrying at its extremity a guide washer 103 abutting a shoulder on the cup and likewise in the position shown in Fig. 1, abutting a stop 104 in the nature of a spring or snap ring slipped into the interior of the reservoir 23. The washer 103 is in contact with an elongated coil spring 106 located within the reservoir and in effect extending for substantially the length thereof. The spring 106 itself does not continue 65 for the entire length of the reservoir, but rather is in abutment with an interposed washer 107 suitably provided with apertures 108 for the passage therethrough of reservoir oil. The washer 107, in turn, is in contact with another coil spring 109 in effect a continuation of the spring 106 and

in abutment with a washer 107 held in the end of the reservoir 23 by a snap-ring 112.

The structure so far described is effective when pressure is exerted on the piston 98 to translate the piston within the cylinder 96 and through the medium of the cup 101 to compress the spring 106 and the spring 109 and thus to maintain the desired pressure on the oil within the accumulator chamber 97. Since the aggregate spring 106 and 109 is quite long, it changes its effective pressure very little with change in length so that substantially a constant pressure is maintained on the oil within the accumulator.

With this structure, the valve 51 can be closed during operation of the pump 21 and still the pump will be effective to open the check valve 46 and to translate the piston 98 toward the left in Fig. 1 to store an accumulation of pressure oil. Upon operation of the valve 51, the stored pressure oil will flow to operate the actuators 16 and 87 and, in the event the pump 21 is not then working, the check valve 46 will close and still a hydraulic pressure system is available. Preferably the capacity of the accumulator with respect to the capacities of the actuators 16 and 87 is such that a number of actuations can occur even if the pump 21 is not operating.

Further in accordance with my invention, I provide means for regulating the flow of oil to the accumulator when the accumulator is substantially full and arrange matters so that not every actuation or depletion will serve to recharge the accumulator. If each slight variation in accumulator capacity served to cause the accumulator to recharge, the mechanism would be working an excessive amount and wear and failure would be accelerated.

In accordance with the invention, therefore, I preferably provide a relief valve in the pressure conduit between the pump 21 and the accumulator 96. This valve is preferably mounted in connection with the head 29 and incorporates a central tube 116 substantially coaxial with the reservoir 23 and serving as a support for a composite valve stem 117, likewise coaxially located within the reservoir and having an open end 118 extending into the filter chamber 36 so that oil flowing into the filter has a by-pass passageway 119 through the hollow interior of the valve stem 117. From the interior of the valve stem, the fluid flows through a number of apertures 121 into the interior of the tube 116. The flow of fluid from the tube 116 is normally prevented by a poppet valve 122 incorporated with the valve stem 117 and normally held on a seat 123 by a surrounding coil spring 124.

The seat 123 is formed in a separate member 125 threaded into the tube 116 for axial translation with respect thereto and is held in any fixed or selected position by a nut 126. When the valve 122 is away from its seat, flow of oil takes place from the interior of the tube 116 through the interior of the member 125 and through apertures 127 therein to the interior of the reservoir 23.

In accordance with my invention, the valve 122 is normally closed, but is opened in response to certain positional effects of the accumulator. For that reason, the valve 117 is provided with an extended stem 128 disposed within the reservoir axially thereof and in the path of the washer 107.

When the accumulator is substantially empty, the washer 107 is spaced from the end of the stem 128 and is ineffective thereon. While the accumulator is filling, however, the washer 107 is translated toward the left in Fig. 1 and eventu-

ally abuts the stem 128 and unseats the poppet valve 122. This valve is an unbalanced valve, being subjected on its enlarged or head side toward the screen or filter chamber 36 to the pressure of the fluid from the pump, although it is exposed on its other or stem side merely to the atmospheric pressure in the reservoir. Furthermore, the coil spring 124 tends to hold the poppet valve on its seat so that in closed position there is considerably more seating pressure on the poppet valve than when it is in its open position, for in that position, while the spring 124 is effective, the hydraulic pressure on opposite sides of the valve is substantially equalized and atmospheric pressure from the reservoir also pervades most of the rest of the structure, even as far as the check valve 46.

Thus, as the accumulator starts to enlarge and move toward the left in Fig. 1, the two springs 106 and 109 are compressed at substantially their combined rate until the washer 107 approximately abuts the stem 128. This movement of the washer is in proportion to but is somewhat less than the axial movement of the accumulator piston, but as soon as the washer contacts the abutment, its progress is arrested due not only to the effect of the spring 124 but due to the hydraulic seating pressure on the unbalanced relief valve. The washer 107 is held in position during further expanding movement or lost-motion of the accumulator until, at a critical point, the pressure from the washer 107 is sufficient to overcome the resistance of the unbalanced valve and the valve opens. Immediately the valve is substantially balanced and the spring 106, which has been excessively compressed with respect to the spring 109, then tends to expand quickly so that equilibrium between the springs 106 and 109 occurs. This results in an abrupt leftward translation of the washer 107 and also of the valve 122, which therefore not only abruptly opens but opens a large amount. As soon, however, as the relief valve opens, the pressure within the pressure lines over to the check valve 46 falls to atmospheric, thus relieving the pump 21 of further pressure load or "unloading" the pump.

The controller valve 51 can be actuated a number of times if desired and when actuated sufficiently causes the accumulator to contract or shrink accompanied by expansion of the two springs 106 and 109. As these springs expand, they drive out fluid under pressure from the accumulator until such time as the washer 107 is partially restored to its initial position and the spring 124 is effective to reseat the poppet valve 122. The re-seating of the poppet valve does not occur at the same accumulator piston position as the un-seating of the valve occurs. That is, the poppet valve is unseated near the extreme expansion of the accumulator, whereas the poppet valve re-seats at approximately one half the contracted volume of the accumulator. As soon as the relief valve 122 is again seated, the pump 21 is effective to build up pressure within the conduits 27 and 38 and again to unseat the check valve 46 when the pressure is sufficient and thereupon to repeat the cycle previously described. With this mechanism, therefore, the accumulator is always maintained in operating condition and is effective to control the "unloading" of the pump, although not every operation of the valve 51 produces a corresponding restoration of the accumulator. Since the relief valve unseats and seats at different accumulator volumes, "hunting" or excessive operation is prevented.

The cycles of operation are illustrated in Figs. 2 to 5 inclusive. As shown in Fig. 2, for example, the pump 21 is operating to draw fluid from the reservoir 23 and is passing it through the conduit 38 inasmuch as the by-pass poppet 122 is closed. It happens that the valve bobbin 54 is in its intermediate or neutral position, so that the line 49 is blocked and hence, the pressure fluid cracks the check valve 46 and causes a displacement of the accumulator piston 98 as the accumulator 10 fills. It will be particularly observed that the washer 107 has come into abutment with the end of the stem 128 of the valve 122 and that the spring 109 is only somewhat compressed, whereas the spring 106 is compressed almost as much as it may be. At this time, the actuator 16 for the brakes, which are applied, and the actuator 87 for the clutch, which is disengaged, are both connected through the valve 51 to the drain line 93 so that they are at atmospheric pressure through communication with the reservoir 23.

In a succeeding stage, as illustrated in Fig. 3, the charging of the accumulator has continued to such an extent that the compression of the spring 106 has translated the washer 107 even farther, so that the poppet valve 122 has suddenly opened, thereby relieving the pressure from the pump 21 and permitting the pump to by-pass through the tube 116 into the interior of the reservoir 23. Since the line 38 is likewise connected to the same passageway, its pressure has dropped to atmospheric and the check valve 46 has been closed due to the higher pressure in the accumulator line. The valve bobbin 54 remains in its central position so that neither the brake actuator 16 nor the clutch actuator 87 is affected. Under these conditions, the pump 21 practically idles since the only power required is to short-circuit the operating fluid through the reservoir at substantially atmospheric pressure. The accumulator, however, is fully charged and is ready for operation.

As shown in Fig. 4, the pump 21 is still operating against substantially an atmospheric pressure. The relief valve 122 remains open because the accumulator 98, although no longer in its largest volumetric or fully translated position, has not yet shrunk sufficiently so that the spring 109 is effective in connection with the spring 124 to close the poppet valve 122. The valve bobbin 54 has been displaced from its intermediate or neutral position, so that pressure fluid from the line 49 has been able to pass through the valve and into the actuator 16 for the brake thus releasing it.

In a comparable fashion, as shown in Fig. 5, the accumulator has been further displaced due to the operation of the brake instrumentality, perhaps a number of times, depending upon the relative volume of the brake actuator and of the accumulator, so that sufficient fluid has been discharged from the accumulator to permit the check or relief valve 122 again to seat, thus blocking the passageway through the tube 116. When this occurs, the pump 21 continuing its rotation and again pumping against the pressure existing within the line 38, quickly builds this up to the pressure within the accumulator chamber 97 so that the check valve 46 again opens and the accumulator begins to refill, thus repeating the former cycle. This figure also shows that the valve bobbin 54 has been translated in the opposite direction from its neutral or intermediate position and is now located so that pressure from the line 49 passes through the valve 51 and is still

effective upon the brake actuator 16, thus holding the brake in released position, and is also now effective upon the actuator 87 for the clutch, thus engaging the clutch. The drain line 93, in this position of the valve, is not connected to either of the actuating devices but remains simply at atmospheric pressure.

In accordance with my invention, therefore, there is provided a structure effective to secure operation a number of times of an actuated instrumentality at the desired pump or fluid pressure value despite variations in operation of the pump itself, even though the pump may for the time being be inoperative. The accumulator is effective to achieve its maximum volume automatically and to unload or relieve the pump of pressure when the accumulator is full, so that the power requirements of the pump are substantially reduced. Furthermore, the accumulator and pressure-relieving instrumentalities are associated with the reservoir in such a way that they are mechanically protected and so that any leakage is immediately drained into the reservoir itself. The arrangement of the relief is such that the system does not "hunt" or continually turn itself on and off with slight variations in accumulator volume, but there is a substantial change in accumulator volume required before the pump unloading mechanism is effective. I provide in accordance with my invention a hydraulic system which achieves the objects mentioned hereinabove and which constitutes a substantial improvement over the prior art.

I claim:

1. A hydraulic system comprising a reservoir, a conduit, a pump withdrawing from said reservoir and discharging into said conduit, a by-pass extending from said conduit to said reservoir, a valve when closed blocking said by-pass, an actuator for said valve extending into said reservoir, a spring in said reservoir, means for flexing said spring, and abutment means associated with an intermediate part of said spring and movable in accordance with the flexure of said part, said abutment means being positioned adjacent said actuator for moving said actuator in a direction to open said valve upon sufficient flexing of said spring.

2. A hydraulic system comprising a reservoir, a conduit, a pump withdrawing from said reservoir and discharging into said conduit, a by-pass extending from said conduit to said reservoir, a valve biased to closed position for blocking said by-pass, an actuator extending into said reservoir for opening said valve upon movement in one direction, a spring in said reservoir, means for flexing said spring, and abutment means associated with an intermediate part of said spring and movable in accordance with the flexure of said part in a direction to open said valve, said abutment means being positioned adjacent said actuator for moving said actuator to open said valve upon sufficient flexing of said spring.

3. A hydraulic system comprising a reservoir, a conduit, a pump withdrawing from said reservoir and discharging into said conduit, a by-pass extending from said conduit to said reservoir, a valve biased to closed position for blocking said by-pass, said valve also being positioned and arranged to resist opening thereof in accordance with the pressure differential in said conduit and said reservoir, an actuator extending into said reservoir for opening said valve upon movement in one direction, a spring in said

reservoir, means for flexing said spring, and abutment means associated with an intermediate part of said spring and movable in accordance with the flexure of said part in a direction to open said valve, said abutment means being positioned adjacent said actuator for moving said actuator to open said valve upon sufficient flexing of said spring.

4. A hydraulic system comprising a reservoir, an accumulator having a moving member associated with said reservoir, a pump, a conduit for supplying said accumulator with fluid under pressure from said pump, a by-pass extending from said conduit to said reservoir, a valve in said by-pass biased to closed position, a spring in said reservoir arranged to be flexed by movement of said moving member, and abutment means associated with an intermediate part of said spring and movable in accordance with the flexure of said part, said abutment means being positioned adjacent said actuator for moving said actuator in a direction to open said valve upon sufficient flexing of said spring.

5. A hydraulic system comprising a reservoir, an accumulator having a moving member associated with said reservoir, a pump, a conduit for supplying said accumulator with fluid under pressure from said pump, a by-pass extending from said conduit to said reservoir, a valve in said by-pass biased to closed position for blocking said by-pass, said valve also being positioned and arranged to resist opening thereof in accordance with the pressure differential in said conduit and said reservoir, a spring in said reservoir arranged to be flexed by movement of said moving member, and abutment means associated with an intermediate part of said spring and movable in accordance with the flexure of said part, said abutment means being positioned adjacent said actuator for moving said actuator in a direction to open said valve upon sufficient flexing of said spring.

6. A hydraulic system comprising a reservoir, an accumulator having a moving member associated with said reservoir, a pump, a conduit for supplying said accumulator with fluid under

10

5

pressure from said pump, a by-pass extending from said conduit to said reservoir, an unbalanced relief valve in said by-pass, a spring for resisting movement of said member, and abutment means associated with an intermediate part of said spring and movable in accordance with the flexure of said part, said abutment means being positioned adjacent said actuator for moving said actuator in a direction to open said valve upon sufficient movement of said member.

7. A hydraulic system comprising a reservoir, an accumulator having a moving member associated with said reservoir, a pump, a conduit for supplying said accumulator with fluid under pressure from said pump, a by-pass extending from said conduit to said reservoir, an unbalanced relief valve in said by-pass normally maintained in closed position responsive to the pressure in said conduit, a spring in said reservoir arranged to be flexed by movement of said member, abutment means associated with an intermediate portion of said spring and movable therewith in accordance with the movement of said moving member, said abutment means being effective in one position of movement of said moving member for opening said relief valve, and means effective in another position of movement of said moving member for closing said relief valve.
